UNITED STATES PATENT OFFICE.

HERMAN A. POPPENHUSEN, OF HAMMOND, INDIANA, AND ARTHUR P. STRONG, OF CHICAGO, ILLINOIS, ASSIGNEES TO GREEN ENGINEERING COMPANY, OF EAST CHICAGO, INDIANA, A CORPORATION OF ILLINOIS.

DROPPAGE-REMOVING MECHANISM FOR STOKERS.

Application filed April 2, 1921. Serial No. 453,036.

To all whom it may concern:

Be it known that we, HERMAN A. POPPENHUSEN and ARTHUR P. STRONG, citizens of the United States, residing, respectively, 5 at Hammond, in the county of Lake and State of Indiana, and Chicago, in the county of Cook and State of Illinois, have invented new and useful Improvements in Droppage-Removing Mechanisms for Stokers, of 10 which the following is a specification.

This invention relates to mechanisms for removing droppage from chain grate and like stokers, and consists in the matters hereinafter described and more particularly set 15 forth in the appended claims.

In the accompanying drawings—

Fig. 1 is a vertical longitudinal sectional view taken through a furnace equipped with a chain grate stoker embodying the drop- 20 page removing mechanism of our invention;

Fig. 2 is a top plan view of said mechanism, the chain grate being omitted for the purpose of illustration;

Fig. 3 is a vertical sectional view taken 25 on line 3—3 of Fig. 1; and

Fig. 4 is a perspective view of one of the step-shaped plates employed in the mechanism.

In Fig. 1 of the drawings, we have shown 30 a furnace equipped with a grate of the progressive feed type, this in the instance illustrated being an endless chain grate 1. The grate 1 is indicated in conventional form and has top and bottom leads 2 and 2^a, which 35 travel over and are supported by skids 3, 3 laterally spaced apart and supported by a number of cross girders secured to and carried by the side members of the grate or stoker structure. One of these girders 4 is 40 at the rear end of the grate just forward of the rear sprocket wheel, and this girder is in the form of a flat plate, arranged vertically to extend between the top and bottom leads of the chain grate, as shown.

At a point forward of the rear girder 4 45 is located a vertically arranged plate 5 extending between the side plates 6, 6 of the stoker structure. This plate 5 is between the top and bottom leads of the chain grate 1, and is hinged along its upper edge to a depending cross member 5^a secured to the upper skids 3 and extending across the grate structure.

Between the girder 4 and the hinged plate

5 are a plurality of horizontally arranged 55 plates 7, 7. These extend between and are secured to the side plates 6 of the stoker structure, as shown in Fig. 3, and are positioned at different levels with respect to each other, ranging from the highest level at the 60 rear cross girder 4 to the lowest level at the plate 5, to thus provide a stepped floor or bottom wall for the compartment formed between the girder 4, plate 5, and that portion of the top lead 2 of the chain grate extending over the compartment, as shown in 65 Fig. 1.

As illustrated in Figs. 1 and 4, each plate 7 has along its rear edge an upwardly projecting, relatively short rib or flange 8 to 70 make the plate step-shaped, and in front of these flanges are arranged pipes 9, 10, 11, and 12, one for each of the plates 7. These pipes extend from one side of the stoker structure to the other and are all 75 closed at one end. The opposite ends of the pipes extend through the adjacent side plate 6 and there connect with a header or main supply pipe 13, which is connected with a source of compressed air supply or steam, 80 if the latter is to be used in lieu of air. Each pipe 9 to 12 has in its length, within the compartment, a plurality of discharge ports or holes, all directed toward the forward end of the grate or toward the hinged 85 plate 5. For opening the plate 5, we provide a manually operable hand lever 14 outside of the furnace, and connect it with the plate 5 by a link 15.

When the damper or plate 5 is open, as 90 shown by dotted lines in Fig. 5, the compartment heretofore mentioned is open, and the portion of the grate 1 above the compartment is under draft. During the operation of the stoker, it is sometimes desirable 95 to cut off the draft to this area of the grate, and this is accomplished by closing the damper 5.

During the operation of the stoker, ash or fuel sifts through the top lead 2 and when 100 over said compartment drops on the step-shaped plates 7, 7. By accumulation, this droppage obstructs the flow of air through the damper 5 when open, and to remove this droppage, compressed air or steam is blown 105 into the pipes 9 to 12, inclusive, and discharged therefrom in a direction toward the open damper 5. This blows the droppage

Between the girder 4 and the hinged plate

out of the compartment on the lower lead of the chain, and from there the droppage sifts through into the hoppers (not shown) below and is then disposed of.

5 By making the floor or bottom of this compartment or chamber stepped, as shown, it is possible to blow all of the droppage out of the compartment, whether the droppage is on the topmost or the bottommost or any 10 of the intermediate plates.

While we have shown and described in detail herein a mechanism for removing droppage from stokers, it is of course to be understood that the details of construction and 15 arrangement of parts illustrated may be variously changed and modified without departing from the spirit and scope of our invention.

We claim as our invention:

20 1. The combination with an endless chain grate, of means forming a droppage collecting compartment between the top and bottom leads of said grate and adjacent the rear end of the same, said compartment being 25 open toward said top lead and having a front opening, a damper controlling said opening, and means in said compartment for blowing droppage therefrom toward the front end of the grate and into the space between said 30 leads when the damper is open.

2. The combination with an endless chain grate, of means forming a compartment ad-

jaacent the rear end of the grate between the top and bottom leads thereof and opening upward toward the top lead, a plurality of 35 step-shaped plates forming the bottom wall of said compartment, the latter having a front opening, a damper controlling said opening, and pipes extending into said compartment in advance of the stepped portions 40 of said plates and having discharge openings directed toward said damper.

3. The combination with an endless chain grate, of front and rear girders spaced apart between the upper and lower grate leads 45 with the front girder immediately below the upper lead and terminating short of the lower lead, a damper plate hinged to the front girder and extending toward the bottom lead, a plurality of step-shaped plates 50 located between the rear girder and said damper plate and successively arranged at different levels with the lowest at the lower edge of the damper plate, and a plurality of pipes arranged one in advance of each 55 of the stepped portions of said plates, said pipes having discharge openings directed toward said damper plate.

In testimony that we claim the foregoing as our invention, we affix our signatures, this 60 30th day of March, A. D. 1921.

HERMAN A. POPPENHUSEN.
ARTHUR P. STRONG.
